PAGE 2

FIGURE 1 is a partial perspective view of an extrusion for sash members or the like embodying my new design;

FIGURE 2 is a partial, rear elevational view of the extrusion shown in FIGURE 1;

FIGURE 3 is a bottom plan view of the extrusion shown in FIGURE 2;

FIGURE 4 is a partial perspective view of another embodiment of an extrusion for sash members or the like employing my new design;

FIGURE 5 is a partial, rear elevational view of the extrusion for sash members or the like shown in FIGURE 4;

FIGURE 6 is a bottom plan view of the extrusion for sash members or the like shown in FIGURE 5;

FIGURE 7 is a partial perspective view of another embodiment of an extrusion for sash members or the like employing my new design;

FIGURE 8 is a partial, rear perspective view of the extrusion for sash members or the like shown in FIGURE 7; and

FIGURE 9 is a bottom plan view of the extrusion for sash members or the like shown in FIGURE 8.

This application is a continuation-in-part of my application Serial No. D. 76,186, entitled Extrusion for Sash Members or the Like, filed August 12, 1963, and now abandoned.

The center of the extrusion in the several views is broken away to indicate an article of indeterminate length.

I claim:

The ornamental design for an extrusion for sash members or the like, as shown and described.
